CLAIM

The ornamental design for a luggage carrier for two-wheeled vehicles, as shown and described.

DESCRIPTION

FIG. 1 is a front perspective view of the luggage carrier for two wheeled vehicles;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a left side view thereof, on a reduced scale showing the luggage carrier on a bicycle and supporting a basket; and,

FIG. 9 is a rear view thereof, on a reduced scale showing the luggage carrier on a bicycle and supporting a basket and side bags.

The bicycle and basket shown in broken lines in FIGS. 8 and 9 and side bags shown in FIG. 9 are shown for illustrative purposes only and form no part of the claimed design.
